FRACTURE APPARATUS

Lloyd A. Straits, Washington, D. C.

Application May 25, 1944, Serial No. 537,257

11 Claims. (Cl. 128—84)

This invention relates to fracture apparatus but is particularly directed to a splint for fractures of the arms, legs and other members of the body.

In fracture apparatus of this type it is necessary in setting the fractures to apply extension or stretching to the limbs or other injured members to adjust the fractured ends of the bones while bandages or splints are applied.

Recognizing this necessity, the present invention combines, in a unitary structure, means for applying extension or stretching and other means for rigidly holding the bones in properly adjusted position while knitting of the fracture occurs.

In accomplishing the foregoing, provision is made for simultaneously applying extension in order that the ends of the fractured bones may be properly adjusted and for forcing the splint firmly against the limb so that movement of the fractured ends of the bone is entirely eliminated.

An object, therefore, of the present device is to provide a simple, combined extension device and splint which may be easily and quickly applied or removed, especially under adverse conditions such as are encountered in the field where facilities for such operation are hard to obtain and still more difficult to apply.

Another object is to produce a combined extension appliance and splint that may be readily transported. To this end, the appliance of the present invention may be rolled or folded so as to require minimum space for storage and which, therefore, may be readily carried as part of the ordinary equipment of medical corpsmen, nurses or the like.

A further object is to produce a device in which pneumatic or other fluid pressure is used to effect the extension and to simultaneously forcibly hold the splints in firm engagement with the fractured member to immobilize the same during healing. If desired heated fluid may be employed where application of heat is desired.

An additional object of the present invention is the production of a device of the character described, in which the weight of the apparatus is reduced to a small fraction of the weight found in similar known equipment so that the same may be worn with greater comfort and will not hamper reasonable movements of the fractured limb as distinguished from the present day heavy plaster cast and similar appliances.

The extension apparatus and splint here described are also designed so that the injured member is engaged somewhat resiliently by both the extension appliance and the splint, while at the same time preventing such movement of the frac-

ture as to cause separation of the bones during healing.

More specific objects of this invention will become apparent from the following description when construed in the light of the accompanying drawing, and the important characteristics are set out in the claims.

In the annexed drawing:

Figure 1 is a plan view of my invention in its flattened condition and before application to the fractured limb.

Figure 2 is a side view of the combined extension apparatus and splint in its applied condition.

Figure 3 is a sectional view taken along the lines 3—3 of Figure 2 but in reversed position.

Figure 4 is a horizontal sectional view on a reduced scale through the splint structure.

Figure 5 is a fragmentary vertical sectional view illustrating the operating mechanism for the extension applying means.

Referring more specifically to the drawing, there is indicated a splint structure generally designated by the reference character 10.

This splint structure comprises a pocketed member made up of a layer of flexible facing fabric, or the like, as indicated at 11. A series of arcuate rigid splint boards 12 lie adjacent the facing fabric 11 and are suitably spaced from each other as indicated in Figure 3. The splint structure is completed by a backing layer of fabric similar to 11 as shown at 13.

The layers of fabric 11 and 13 are secured to each other at their side margins by stitching, gluing or the like as at 14 and may be likewise secured at both ends as indicated at 15, although this is not essential in all cases. By leaving one or both ends of the fabric unsecured, the splint boards 12 may be readily inserted or removed.

The splint boards 12 are held in properly spaced position by rows of stitching, gluing or the like, as at 16, which secure the facing and backing fabrics together along lines lying between the splint boards to form a plurality of pockets 17, extending from end to end of the splint structure.

Within the pocket 17 the splint boards 12 are placed, as will be obvious, it being understood that the boards are of proper size, rigidity and curvature, depending upon the nature of the fracture and the limb involved.

The splint structure is applied to the fractured limb simply by wrapping the same about the injured member so as to bridge the fracture and securing it in this position by means of tapes,

cords or the like, as shown at 18, which are attached to the corners of the splint structure 10.

After the splint structure has been applied, it must be forcibly held in firm engagement with the limb to immobilize the fractured ends of the bones, while at the same time extension or stretching must be applied to the limb on opposite sides of the fracture in order that the fractured ends of the bones may be properly adjusted. This force must be applied in opposite directions on opposite sides of the fracture so as to tend to separate the fractured ends of the bones.

This is accomplished in the present invention by means of an inflatable envelope or bag 19 which shall now be described.

The envelope or bag 19 is made of rubber, rubberized fabric or other flexible, extensible, inflatable material and consists of two sheets 20 and 21, which are stitched, glued or otherwise secured together at their margins, as seen at 22, to form a chamber 23 for the reception of air for inflating the envelope 19.

Inflation may be accomplished by means of a tube 24, communicating with the chamber 23 and being held against the side of the bag by a strap 25. The bag 19 may be inflated by mouth, pump or by attaching a capsule of carbon dioxide gas to the tube 24, it being understood that any suitable check valve is used to prevent escape of air from the bag 19 through the tube 24.

The bag 19 is wider than the splint structure 10 as seen in Figure 1 and has its inner wall 20 glued or otherwise attached to the backing fabric 13 of the splint structure 10 so that the bag 19 and the splint structure 10 are permanently secured together to form a simple, readily applicable and light weight fracture apparatus.

In order that the fractured ends of the bones may be adjusted for proper alignment and positioning, extension or stretching is applied to the limbs as previously described. This is accomplished by the present invention in an extremely facile manner by uniting to the bag or envelope 19 a plurality of light weight cylinders as indicated at 26 and 27. These cylinders are carried by looped brackets 28 and 29, secured to the bag 19 at points spaced longitudinally of the cylinders although of course they may be secured in any desired manner. While only two of the cylinders 26 and 27 are illustrated as being positioned on opposite sides of the bag 19, it will be understood that any desired number may be used and their position is optional so long as they will supply the proper extension to the injured limb.

Reciprocating in each cylinder is a pair of pistons 30 and 31 carried by rods 32 and 33 which extend axially of the cylinders and project from opposite ends thereof as indicated at 34 and 35. The ends of the rods are offset as at 36 and 37 in the direction of the limb being treated so as to lie closely adjacent thereto.

The free ends of the rods are secured to the fractured limb by straps 38 and 39 attached to the ends of the rods and are adapted to encircle the limb on opposite sides of the fracture.

It will be seen from the foregoing that as the pistons 30 and 31 move away from each other, extension or stretching is applied to the fractured limb through the rods 34 and 35 and straps 38 and 39, the extent of stretching being determined by the pressure of air introduced into the bag 19.

Pistons 30 and 31 are caused to move in op-

posite directions by means of a collapsible bellows 40, housed in each of the cylinders 26 and 27 and located between the pistons 30 and 31. Expansion of the bellows is confined to the direction of the length of the cylinders and consequently moves the pistons 30 and 31 in opposite directions.

Air or other fluid pressure is supplied to the bellows 40 through a suitable conduit here illustrated as a hollow rivet 41 secured to the bag 19 by a flange 42 and projecting through aligned openings 43 in the cylinder 26 and bellows 40 to which it is fastened by a flange 44.

It will thus be seen that as the bag 19 is inflated, the air therefrom passes through the hollow rivet 41 into the bellows 40 and expands the same so as to force the piston rods 32 and 33 in opposite directions to apply the proper extension or stretch to the afflicted limb.

The combined extension appliance and splint is readily and quickly applied by first wrapping the splint structure about the fractured limb and securing it in position by the tapes 18. The bag 19 is simultaneously wrapped with the splint structure and the edges of the bag are secured together by means of a separable fastener such as the well known "zipper" fastener. This fastener comprises interengaging members 45 and 46, secured along respective edges of the bag, the interengaging members being interlocked with each other by means of a slide 47 in conventional manner.

The appliance is applied so that the splint structure lies next to the leg, or other limb, and extends across the fracture. The extension rods are then strapped to the injured limb above and below the fracture by the straps 38 and 39. The appliance is then ready for inflation.

This is accomplished by forcing air through the tube 24 either orally, by pump or from a carbon dioxide cartridge attached thereto. Air flowing through the tube 24 inflates the bag 19 and forces the splint boards firmly into position, it being noted as shown in Figure 3 that the splint boards are so spaced and shaped that the edges lie closely adjacent to each other to form in effect a complete cylindrical splint.

At the same time that the splint is being forced into proper position to immobilize the fractured ends of the bones, air is also passing into the bellows 40, causing opposite movement of the rods 32 and 33 and consequently applying extension or stretching in the desired manner so that the fractured ends of the bones are brought into proper position where they are firmly held by the splint structure.

It will thus be seen that one of the outstanding features of the present invention resides in the fact that the simultaneous application of stretching and application of the splint structure to immobilize the fractured joint is accomplished. Furthermore, it is apparent that the foregoing operations are performed quickly and easily by the simple expedient of strapping the splint and its surrounding inflatable bag around the fractured limb and then inflating the bag.

While the invention has been illustrated and described in its preferred embodiment, it will be understood that changes in size, materials, and other details of construction may be resorted to so long as they fall within the spirit and scope of the invention as defined by the appended claims.

I claim:

1. Fracture apparatus for legs, arms or similar

members, comprising a splint structure, extension applying means carried by said splint structure, means for securing the splint structure and extension applying means to the fractured member and means for simultaneously forcing the splint against the fractured member and applying tension thereto.

2. Fracture apparatus for legs, arms or similar members, comprising a splint structure, extension applying means carried by said splint structure, means for securing the splint structure and extension applying means to the fractured member and pneumatic means for simultaneously forcing the splint against the fractured member and applying tension thereto.

3. Fracture apparatus comprising a splint structure, inflatable means surrounding said splint structure and operable to force the splints into firm engagement with the fracture member to immobilize the same, and extension means attached to the inflatable means and operable by the inflation of the inflatable means to apply tension to the injured member on opposite sides of the fracture.

4. Fracture apparatus comprising a splint structure, an inflatable member secured to and surrounding the splint structure when the same is applied, extension means carried by the inflatable member and means for operating said extension means comprising an expandible chamber communicating with said inflatable member and being expandible upon inflation of the inflatable member.

5. Fracture apparatus comprising a splint structure, said structure consisting of spaced layers of flexible material secured together at their margins to form an enclosure, a plurality of spaced arcuate rigid splint boards in said enclosure and a flexible bag secured to the outer wall of said splint structure and operable upon inflation to forcibly press the rigid splint boards against the fractured member to immobilize the same.

6. Fracture apparatus comprising a splint structure consisting of a flexible envelope having rigid splint boards therein and capable of being wrapped about a fracture member, an inflatable bag secured to the outer wall of the splint structure and surrounding the same when the splint structure is applied, extension mechanism carried by said bag and means for securing said extension mechanism to the fractured member on opposite sides of the fracture, said extension mechanism being operated to apply tension when said bag is inflated.

7. Fracture apparatus comprising a flexible splint structure consisting of spaced layers of fabric with intermediate rigid splint boards spaced from each other and forming substantially a cylindrical splint when applied to a fractured member, an inflatable bag surrounding said splint structure and having its free edges secured together by a separable fastener means for inflating the bag, extension mechanism carried by said bag and comprising a plurality of cylinders, pistons slidably mounted in said cylinders and operable to move in opposite directions, means for connecting said pistons to the fractured member above and below the fracture and means for moving the pistons in opposite directions.

8. Fracture apparatus comprising a flexible splint structure provided with rigid splint boards, said structure being capable of being wrapped

around a fractured member, an inflatable bag surrounding said splint structure and operable upon inflation of the bag to force the splint structure into firm engagement with the fractured member, spaced cylinders carried by said bag, means for affording communication between the interior of said bag and the interior of said cylinders, pistons movable in said cylinders in opposite directions and carrying means thereon for connecting the same with the fractured member above and below the fracture, said pistons being moved in opposite directions upon inflation of the bag.

9. Fracture apparatus comprising a splint structure embodying spaced sheets of flexible material secured together at their margins, said structure provided with spaced rows of stitching extending the full length thereof to provide individual pockets for a plurality of rigid splint boards, said boards being arcuate in formation so as to form a substantially cylindrical splint when the structure is wrapped about a fractured member, an inflatable bag surrounding said splint structure when in applied position, cylinders carried by said inflatable bag and being provided with spaced pistons movable in said cylinders in opposite directions, means affording communication between the interior of the inflatable bag and the cylinders and a bellows interposed between the spaced pistons and receiving fluid from the bag when the bag is inflated, said pistons carrying means for securing the same to a fractured member above and below the fracture.

10. Fracture apparatus comprising a splint structure consisting of spaced sheets of fabric secured together at their side margins and being provided with a plurality of adjacent pockets, a rigid splint board carried in each pocket, and having arcuate form so as to form substantially a cylindrical splint surrounding the fractured member when the splint structure is wrapped thereabout, means for retaining said splint structure in its wrapped condition, an inflatable bag surrounding said splint structure when in applied condition and having its free edges secured together by means of a separable fastener, extension members attached to said bag comprising means for applying stretch to the injured member on opposite sides of the fracture, said members including tapes encircling the injured member above and below the fracture for securing the extension members in place.

11. Fracture apparatus comprising a splint structure, including spaced sheets of flexible material secured together at their side margins and being provided with spaced rows of stitching between the margins to form individual pockets extending longitudinally of the splint structure, arcuate shaped rigid splint boards positioned in each pocket, said splint structure being adapted to be wrapped about a fractured member so as to form a substantially cylindrical splint completely surrounding said member, means for applying pressure uniformly about the circumference of said splint structure when in applied position and extension mechanism carried by said last-named means and secured to the injured member above and below the fracture whereby tension may be applied to said injured member simultaneously with the application of pressure to the splint structure.

LLOYD A. STRAITS.
